UNITED STATES PATENT OFFICE.

EDWARD F. JONES, OF ST. JOSEPH, MISSOURI.

STEAM-TRAP.

1,078,047.

Specification of Letters Patent.

Patented Nov. 11, 1913.

Application filed January 15, 1913. Serial No. 742,114.

To all whom it may concern:

Be it known that I, EDWARD F. JONES, a citizen of the United States, residing at St. Joseph, in the county of Buchanan and State of Missouri, have invented a new and useful Steam-Trap; and I do hereby declare the following to be a full, clear, and exact description of the invention, such as will enable others skilled in the art to which it appertains to make and use the same.

This invention relates to a new and useful steam trap.

As one of the objects of the invention it is the aim to provide a trap of this nature, adapted for use in connection with low pressure apparatus, it being the design of the invention to discharge the water from the trap without the loss of more than an ounce of steam.

Particularly the trap is adapted for use in connection with heating coils, vats or tanks, where low pressure steam is used, and through experience it has been found that it handles condensation of steam as fast as it is supplied, thereby keeping full pressure on the heating coils or tanks.

There are disclosed in the drawings certain features of construction, but in practical fields, these features may necessitate alterations, to which the patentee is entitled, provided the alterations fall within the scope of what is claimed.

The invention comprises further features and combination of parts, as hereinafter set forth, shown in the drawings and claimed.

In the drawings:—Figure 1 is a vertical sectional view through the improved trap. Fig. 2 is a cross sectional view.

Referring more particularly to the drawings 1 designates a cylinder, which may be of any suitable dimension or proportion. Fastened to the upper end of the cylinder by means of bolts 2 is a cap plate or head 3, there being suitable packing 4, in order to insure the steam tight connection. A nipple tube 5 is threaded or otherwise secured in the cap plate or head, as shown at 6. The nipple tube is supplied with an air cock or valve 7, for allowing the escape of air. An inlet pipe 8 connects to the cylinder 1, for feeding steam to the same. The lower end of the cylinder 1 terminates in an annular flange 9, which is arranged adjacent another flange 10, there being bolts 11 for securing the cylinder and the attendant parts

to any form of heating coils, vats or tanks (not shown).

An outlet pipe 12 extends from the interior of the cylinder 1, and terminates at any suitable location upon the exterior of the cylinder. This pipe 12 is provided with a valve casing 13 having the usual valve 14, to the stem 15 of which an arm 16 is secured. Slidable upon the arm 16 is a collar 17, held in adjusted positions upon the arm 16 by the set screw 17^a. To this collar the flexible end 18 of the rod 19 is pivotally connected. The upper portion or extremity of the rod 19 is guided in the nipple tube as it moves vertically. Slidable loosely upon the rod 19 is any suitable construction of float 20. On the rod 19 immediately above its flexible end portion 18, and fixed below the float 20 by means of the set screw 20^a is a collar 20^b, which supports the float 20, above the flexible end 18. Arranged upon the rod 19, the same being held in adjusted positions by a set screw 21 is a collar 22. This collar may be set at any location upon the rod 19, according to when it is desired that the valve 14 should open to allow the water in the cylinder 1 to escape. The steam enters the cylinder 1 by way of the pipe 8, and as the steam condenses, the water settles in the bottom of the cylinder, and if the collar 22 is set at *a* on the rod 19 and the water reaches a level as indicated at *a*¹, the float 20 will contact with said collar 22 and raise the rod vertically, which in turn will open the valve 14 and permit the water to escape through the pipe 12. However, the collar 22 may be set at *b* on the rod 19, and when the water rises to a level as indicated at *b*¹, the float 20 will contact with the collar 22, in order to raise the rod, which in turn will actuate the valve 14, to allow the outflow of the water.

The object in adjustably connecting the lower flexible end 18 of the rod 19 to the rod 16, is to increase or decrease the throw of the valve 14, in opening and closing. The object for allowing the valve to open at different levels of the water in the cylinder 1, is to allow an attendant of a low pressure plant to adjust the trap, according to the nature and the operation of such a plant.

It is to be ascertained from the foregoing that there has been devised a simple and efficient steam trap, and one which has been found more particularly adapted for use in

connection upon low pressure apparatus, owing to the practicability of the construction.

The invention having been set forth, what is claimed as new and useful is:—

- In a steam trap, a cylinder having a steam inlet and provided with an outlet pipe having a valve, said valve having an arm movable therewith, a nipple tube including an air cock connected to the cylinder, a rod movable in said cylinder with its upper portion slidable in the nipple tube and having a lower flexible end, a collar mounted on said arm to which the lower extremity of said flexible end is pivotally connected, said collar adapted to be adjusted in different posi-

tions to vary the throw of the valve including a device for holding the same adjusted; a float slideable on said rod, a collar on said rod above its flexible end and fixed below the float, a second collar arranged adjustably on said rod above the float and with which adjustable collar said float contacts when raised by the accumulation of water in the cylinder to move the rod vertically. 20

In testimony whereof I have signed my name to this specification in the presence of two subscribing witnesses.

EDWARD F. JONES.
